UNITED STATES PATENT OFFICE.

SAMUEL M. CLEMENT, OF WEBSTER GROVES, MISSOURI, ASSIGNOR TO BUDD WHEEL COMPANY, OF DETROIT, MICHIGAN, A CORPORATION OF PENNSYLVANIA.

WIRE AND DISK WHEEL SPLIT-RING TOOL.

Application filed August 9, 1926. Serial No. 128,298.

My invention relates to a wire and disk wheel split ring tool and the method of using same, and, it is a distinct and practical improvement to overcome certain objections to, 5 and defects in the tools now employed for removing the split retaining ring from wire and disk wheels for motor vehicles.

An object of my present invention is the provision of a flat tool having a curved 10 tapered end provided with longitudinally grooved faces adapted to be inserted into the split, or gap between the ends of a split tire retaining ring for quickly and conveniently lifting one end of the retaining ring from its 15 seating groove in the wheel rim prior to removing the ring from the wheel rim.

Another object of the invention is to provide the flat outer curved faces of the tool with longitudinal grooves for receiving the 20 ends of the retaining ring to prevent the tool from slipping laterally when applying pressure to the handle end of the tool in lifting one end of the ring from its seating groove.

25 Another object of the invention is the method of inserting the flat curved facial grooved tapered end of the tool in the narrow slit between the ends of the ring so that the front grooved face of the tool will engage under one end of the ring while the rear channeled face of the tool will engage the high corner of the opposite end of the ring which acts as a fulcrum point so that the tool can be used as a lever for prying one 30 end of the ring out of the rim groove prior to removing the ring from its seating groove in the wheel rim.

A still further object of the invention is the provision of a wire and disk wheel split 40 ring tool which possesses advantages in points of simplicity and efficiency, and, at the same time proves itself comparatively inexpensive in cost of manufacture.

With the above and other objects in view, 45 the invention consists in the novel features of construction, arrangement and combination of parts hereinafter more fully described and finally pointed out in the claims hereto appended.

50 Referring to the accompanying drawings forming a part of this specification, wherein like characters of reference denote similar parts throughout the several views:

Fig. 1, is a vertical sectional view of a tool

constructed in accordance with my invention. 55

Fig. 2, is a front perspective view of the lower curved end of the tool.

Fig. 3, is a rear perspective view of the 60 lower curved end of the tool.

Fig. 4, is a transverse sectional view taken on line 4—4 of Fig. 1.

Fig. 5, is a perspective view of a portion of a wheel rim showing the seating groove and a portion of the split tire retaining ring. 65

Fig. 6, is a side elevation of a portion of a wheel rim and the split ring applied thereto with the tool shown in position to lift one end of the ring from its seating groove.

Fig. 7, is a view similar to Fig. 6, showing one end of the ring lifted from its seating groove. 70

Fig. 8, is a view illustrating the use of the tool in replacing the ring upon the wheel rim. 75

Referring to the drawings, the reference numeral 1 represents a section of a wire or disk wheel rim having the inner tire bead retaining flange 2 and provided at its outer edge with the peripheral groove 3 which is adapted to receive and retain the split retaining ring 4 which is formed with the integral outer tire bead retaining flange 5, as clearly shown in Fig. 5. One end of the split ring 4 is undercut, as at 6 and provided with the inner cutaway portion 7. When the ring 4 is positioned in the groove 3 of the wheel rim 1, there is provided a split, or gap 8, as shown in Fig. 5. 80

The tool embodying the features of my invention for carrying out my method of removing split rings from wire and disk wheel rims and replacing the same, comprises a suitable, preferably flat handle section 9. This handle section 9 is longitudinally curved upwardly at its lower end, as at 10 to provide the front concaved face 11 and the back convexed face 12. The curved lower end 10 of the handle 9 is tapered as to both width and thickness, as clearly shown in Figs. 2 and 3, so as to be readily inserted into the narrow slit, or gap 8 between the adjacent ends of the split ring 4, as clearly shown in Fig. 6. 85

The front face 11 of the tool at the lower end of handle 9 is provided with a suitable longitudinal groove, or channel 13, while the back face 12 of the tool at the lower end of 90

95

100

105

the handle 9 is provided with a longitudinal groove, or channel 14, which latter channel 14 is longer than the front channel 13. Both channels preferably extend into the straight 5 faces of the tool, as shown in Fig. 1.

The rear flat face of the handle 9 is provided at a suitable distance from the lower curved end 10 of the tool with a suitable flat transverse shoulder 15, which affords means 10 to engage the upper edge of the ring flange 5 of the ring 4 to prevent the free end of the ring from climbing up on the tool handle 9 when forcing the ring back into its rim seating groove 3 when replacing the ring 4 upon 15 the wheel rim 1, as clearly shown in Fig. 8.

From the foregoing description and by referring to Figs. 6 and 7, it is evident that I provide a flat rim ring tool, which when inserted into the gap 8 between adjacent ends 20 of the ring flange 5 will permit the lower curved end of the tool handle to enter the undercut portion 6 of the ring flange 5 with the lower corner 16 of one end of the ring in engagement with the upper facial groove 25 13 while the upper corner 17 of the opposite end of the ring will engage in the rear facial groove 14 and act as a fulcrum point for the handle to swing upon, when forcing the handle 9 downwardly toward the rim for raising 30 the curved inner end of the handle which lifts one end of the ring from its ring seating groove, as clearly shown in Fig. 7. It will be readily seen that the facial grooves of the tool prevents the tool from slipping 35 laterally upon the corners of the split ring when prying one end of the ring from its ring seating groove.

The many advantages of the herein described invention will readily suggest themselves to those skilled in the art to which it 40 appertains.

I do not wish to be understood as having limited myself to the details of construction shown and described, but desire to have it 45 understood that the invention I have shown in the drawings is merely illustrative, as it is manifest that various minor changes may

be made in the exact construction and particular arrangement of parts without departing, from the spirit of my invention 50 hence I reserve the right to make any such changes, or modifications as may fairly fall within the scope of the appended claims when fairly construed.

What I claim is:

1. A non-cutting tool for removing tire-retaining rings comprising an operating shank having an end adapted to be inserted longitudinally between the meeting ends of a tire retaining ring in place on a vehicle wheel and beneath the one end, which shank end is provided with means projecting within the perimeter of the locking ring when the tool is inserted to laterally interlock with at least one of the meeting ends of the ring. 60

2. A non-cutting tool for removing tire retaining rings comprising an operating shank having an end adapted to be inserted longitudinally between the meeting ends of a tire retaining ring in place on a vehicle wheel and beneath the one end, which shank end is provided on its opposite sides with longitudinally extending reentrant surfaces adapted to laterally interlock with the upper and lower edges respectively of the meeting 70 ends of the ring. 75

3. A non-cutting tool for removing tire retaining rings comprising an operating shank having an end adapted to be inserted longitudinally between the meeting ends of a tire retaining ring in place on a vehicle wheel, said end being provided with longitudinally extending reentrant surfaces on its opposite sides, constituting non-communicating grooves adapted to laterally interlock with the upper and lower edges respectively of the meeting ends of the ring to a depth relatively shallow as compared with the depth of transverse cross-section of the ring itself. 80 85 90

Signed in the city of St. Louis and State of Missouri this 7 day of July, A. D. 1926.

SAMUEL M. CLEMENT.
